PRESSURE-CHAMBER FOR REMOVING DIVERS' DISEASES.

1,294,188.

Specification of Letters Patent. Patented Feb. 11, 1919.

Application filed May 25, 1915. Serial No. 30,308.

To all whom it may concern:

Be it known that I, HERMANN STELZNER, a citizen of the German Empire, residing at Lübeck, in the German Empire, have invented a certain new and useful Improved Pressure-Chamber for Removing Divers' Diseases, of which the following is a specification.

When a diver comes up quickly from a great depth to the surface of the water the nitrogen taken up by the diver's body while under the high pressure of the water at said great depth, is expelled in the form of bubbles. The most deadly divers' diseases may be produced by this occurrence, if preventive measures are not taken promptly to counteract the same. Such measures are: immediately again sinking the diver to a certain depth of water or putting him into a steel-chamber in which he is subjected to an air pressure corresponding to the pressure exerted by the water at said certain depth. By this means, that is to say, by bringing the body again under pressure, the gas bubbles will be reabsorbed and rendered harmless. The diver can be protected from the injurious consequences of the above mentioned expulsion of nitrogen bubbles only by pulling him up and out of the water very slowly or by very slowly decreasing the air pressure in the steel-chamber in which the diver has been placed.

To sink a diver again is not always possible and convenient, as a heavy sea may be running, or the weather or tide may prevent such measure, or the diving armor may be in disorder, or the diver himself may be injured. It also happens that the major symptoms of the influence of the nitrogen sometimes make their appearance quite suddenly, often after the diving armor has been taken off. In these circumstances it is almost impossible, to dress the diver again in the armor, and ordinarily a steel-chamber which might be used as a pressure-chamber, is not present on board of a diver's boat because there is not room enough and the operation of such a steel-chamber requires expensive devices for producing and circulating the necessary compressed air, in order that the said cures may be continued for about 6 to 10 hours as is necessary.

There is still a third method whereby the formation of bubbles of nitrogen received

in the body may be counteracted. This method consists in laying the diver on deck fully clothed or armored and forcing air into the cloth or armor by means of a pump, in which case care must, however, be taken at the same time to produce a circulation of the said air. As already stated, it is not always possible to again clothe or armor the diver if the symptoms of the disease do not appear until after the undressing of the diver has taken place. Besides this an ordinary diving cloth does not possess a sufficient amount of resistance to stand a pressure of 1 to 3 atmospheres above atmospheric pressure.

According to the present invention the drawbacks stated above are obviated by means of a foldable or collapsible receptacle adapted to be used as a pressure-chamber in which the diver may be treated after being taken ill. To serve this purpose the said receptacle is constructed to inclose the whole body of the diver like a bag and to allow of a hermetical closing. The said receptacle is moreover provided with the necessary connecting branches and nipples for connection with the devices whereby the receptacle is placed under inner air pressure and the compressed air is regenerated. To the receptacle are also attached suitable means for indicating and for adjusting the air pressure.

A constructional form of the improved collapsible pressure-chamber made in accordance with and embodying the invention, is illustrated, by way of example, in the accompanying drawing, in which:

Figure 1 is a side elevation of the collapsible pressure-chamber when in use for treating a diseased diver, and

Fig. 2 is an end view of the head of the said pressure-chamber.

The pressure-chamber consists of a bag-shaped receptacle *a* made of strong waterproof or india-rubber cloth, preferably tapering toward its closed or foot-end and adapted to receive and inclose the whole body of a diver. The open or head end of this receptacle in the construction and arrangement shown is provided with a rigid, apertured end member, illustrated best in Fig. 2, which in addition to its other functions is adapted, by resting upon a surface, to support said open end of the receptacle

in an upright position transverse to the major axis thereof, when said receptacle occupies the horizontal position shown in Fig. 1; said end member also carries a rigid 5 cover, for example, a metal plate *b* whereby the open end of the receptacle is closed and which at the same time forms the support or carrier of the fittings necessary for working the said device. The fittings comprise 10 a connecting branch *c*¹ having a cock *c* and adapted to receive one end of the flexible tube *d*¹ communicating with a steel cylinder *d* containing compressed air, a branch *e*¹ provided with a blow-off cock *e*, a pressure- 15 gage *f*, a safety valve *g* and two connecting branches *h* and *i* for attaching an air regenerating device *k* of well known construction, such as are used, for example, in connection with smoke protecting helmets or 20 tubeless diving apparatus.

The improved pressure chamber may be used as follows: The diseased diver is put, his feet first, into the open receptacle *a*. His head is comfortably and so supported that 25 it can be observed through a window *m* provided in the wall of the receptacle *a*. The latter is then closed air tight or hermetically by the cover *b*, and the regenerator *k* connected to the branches *h*, *i* and the compressed air cylinder *d* to the branch *c*¹. After this compressed air is passed into the receptacle *a* until the required pressure is obtained which will be indicated by the pressure gage *f*, too high a pressure being 30 prevented by the safety valve *g*. The diver within the receptacle is then surrounded by compressed air of the desired predetermined pressure so that his lungs are breathing under this pressure, while the breathing air current is circulating in a well known manner through the regenerating device *k* and continuously regenerated by the latter. When the state or condition of the diver permits it, the compressed air is allowed 35 to blow off slowly through the cock *e*. This decrease of pressure in the receptacle *a* must be effected stepwise and each succeeding step must last for a longer period of time than the preceding until the atmospheric 40 pressure is reached and the danger to the diver thus removed. The said decrease of pressure can be simply and easily brought about by means of the blow-off cock *e*.

The same effect may also be obtained by 45 means of a diver's pump connected with the receptacle *a* in any suitable manner. With such arrangement fresh external air is continuously pumped or pressed into the receptacle while the consumed or exhausted 50 air blows off constantly through the safety valve *g*, this operation being exactly the same as with an ordinary diving apparatus. The compressed air cylinder *d* and the regenerating device *k* are then entirely dispensed with.

In order to obviate the necessity for making the receptacle *a* of excessively heavy or thick material it is advisable, to surround the receptacle with a protecting net *a*¹ of wire rope, hemp rope or chain links. 70

The receptacle *a* forming the pressure-chamber may be easily and readily folded or collapsed to form a relatively small bundle or packet which can be stowed away and transported in a small box or the like. Every small diver's boat can therefore readily take such a pressure-chamber to the diver's working place, so that the same may always be at hand ready for immediate use, when the diver comes up. Needless to say that 80 in cases of disease of the indicated type it is of the utmost importance to start the pressure treatment as quickly as possible.

I claim:

1. An apparatus of the kind described 85 comprising a flexible sack-shaped receptacle adapted to contain a human body for treatment by compressed air and rigid means attached to said receptacle at one end for supporting said end in an upright position 90 transverse to the major axis of the receptacle.

2. An apparatus of the kind described comprising a flexible sack-shaped receptacle adapted to contain a human body for treatment by compressed air; rigid means attached to said receptacle at one end for supporting said end in an upright position 95 transverse to the major axis of the receptacle, and a protective netting extending from said rigid means and completely enveloping 100 said receptacle.

3. An apparatus of the kind described comprising a flexible sack-shaped receptacle having a closed and an open end and adapted 105 to contain a human body in its entirety, a rigid end member connected with the open end of said receptacle and arranged to support said open end in an upright position transverse to the major axis of the receptacle, a rigid cover movably connected with said end member for hermetically sealing said receptacle, and fittings carried by said cover whereby said apparatus may be operatively utilized.

4. An apparatus of the kind described 115 comprising a flexible sack-shaped receptacle having a closed and an open end and adapted to contain a human body in its entirety; a rigid end member connected with the open end of said receptacle and arranged to support said open end in an upright position 120 transverse to the major axis of the receptacle, a rigid cover movably connected with said end member for hermetically sealing said receptacle and a rigid fitting including 125 a window connected with said receptacle through which the interior thereof is visible.

5. An apparatus of the kind described comprising a collapsible sack-shaped receptacle adapted to contain a human body 130

and tapering toward its closed end, a rigid end member connected with the open end of said receptacle and arranged to support the same, a rigid cover movably connected with 5 said end member for hermetically sealing said receptacle, fittings carried by said cover whereby said apparatus may be operatively

utilized and a protective netting surrounding said receptacle.
